Primary Examiner — Jack Reickel*Assistant Examiner* — Keith J Wilson(74) *Attorney, Agent, or Firm* — Womble Bond Dickinson (US) LLP(57) **CLAIM**

The ornamental design for a shower head, as shown and described.

DESCRIPTION

FIG. 1 is an isometric top view of a shower head according to our new design;

FIG. 2 is an isometric bottom view thereof;

FIG. 3 is a left side view thereof;

FIG. 4 is a right side view thereof;

FIG. 5 is a front view thereof;

FIG. 6 is a bottom view thereof;

FIG. 7 is a top view thereof;

FIG. 8 is an enlarged view of a portion of the shower head indicated in FIG. 1; and,

FIG. 9 is an enlarged view of a portion of the shower head indicated in FIG. 2.

The views not shown form no part of the claimed design.
